(57) **CLAIM**

The ornamental design for a remote control, as shown and described.

DESCRIPTION

FIG. 1 is a perspective view illustrating a remote control design;

FIG. 2 is a front view illustrating a remote control design;

FIG. 3 is a back view illustrating a remote control design;

FIG. 4 is a side view illustrating a remote control design;

FIG. 5 is another side view illustrating a remote control design;

FIG. 6 is a top view illustrating a remote control design;

FIG. 7 is a bottom view illustrating a remote control design; and,

FIG. 8 is a perspective view illustrating a remote control design.

The broken lines in the figures depict portions of the remote control that form no part of the claimed design.
